UNITED STATES PATENT OFFICE.

JAMES M. SMITH AND JOHN H. SMITH, OF FAIRCHILD, WISCONSIN.

POTATO-PARING MACHINE.

1,001,558.

Specification of Letters Patent. Patented June 10, 1913.

Application filed March 29, 1911. Serial No. 617,639.

To all whom it may concern:

Be it known that we, JAMES M. SMITH and JOHN H. SMITH, citizens of the United States, residing at Fairchild, in the county of Eau Claire and State of Wisconsin, have invented new and useful Improvements in Potato-Paring Machines, of which the following is a specification.

This invention relates to machines or devices for cleaning and paring fruits and vegetables, such as potatoes and the like, in a convenient and expeditious manner, and it has for its object to simplify and improve the construction and operation of this class of devices.

With these and other ends in view which will readily appear as the nature of the invention is better understood, the same consists in the improved construction and novel arrangement and combination of parts which will be hereinafter fully described and particularly pointed out in the claim.

In the accompanying drawings has been illustrated a simple and preferred form of the invention, it being, however, understood that no limitation is necessarily made to the precise structural details therein exhibited, but that changes, alterations and modifications within the scope of the claim may be resorted to when desired.

In the drawings.—Figure 1 is a perspective view showing a simple and preferred form of the improved potato paring machine. Fig. 2 is a vertical transverse sectional view. Fig. 3 is a longitudinal sectional view taken on the line 3—3 in Fig. 2.

Corresponding parts in the several figures are denoted by like characters of reference.

In the construction of the machine, as illustrated in Figs. 1, 2 and 3, there is provided a trough or casing A which may be formed of two boards 1, 1 of suitable dimensions which are connected together at a suitable angle to form a V-shaped trough, the ends of which are obstructed by rectangular end pieces 2, 2 which may be nailed upon or otherwise suitably connected with the ends of the boards or side members 1, 1. The rectangular end pieces form a large supporting

bench or table or upon a supporting frame of any suitable character. One of the side members 1, 1 is extended upwardly so as to form a curved shield or deflector 3 which extends the full length of the casing and which affords a shield to prevent the operator from being splashed when the machine is in operation.

The end members 2, 2 are provided with bearings for a shaft 4 having at one end a cylindrical cylinder 5 which may be rotated. The shaft 4 carries a cylindrical casing 6 which is preferably constructed of sheet metal with holes apertured and provided with inwardly extending serrated or teethed abrading cylinders 7. The cylindrical casing 6 includes a hinged or supported lid or closure 8 to enable the potatoes or other vegetables or fruits which are to be operated upon to be conveniently introduced and removed.

The shaft 4 is equipped with an auxiliary grating or abrading cylinder 9 having outwardly extending abrading teeth 10. The ends of the cylinder 9, which terminate within a short distance of the ends of the cylindrical casing 6, are open and constructed to admit of the ready discharge of the gratings or parings.

In the operation of this device the potatoes or other vegetables or fruits that are to be cleaned and pared are placed within the cylinder 6, which is partly immersed in water which is introduced in the water trough or casing. The cylinder is now rotated, thus subjecting the contents to the abrading action of the grating teeth, whereby the outer skin will be removed, and the vegetables or fruits will be quickly and effectively cleaned and pared. After the completion of the operation the contents of the cylinder 6 may be readily removed by opening the door or closure 8, and the water contained in the trough or outer casing may be then readily poured or discharged from the same.

Having thus described the invention, what is claimed as new, is—

In a cleaning and paring device, a trough, a shaft supported for rotation thereon, a cylindrical cylindrical casing carried by a said shaft and having a hinged closure and

inwardly extending abrading members, and
an abrading cylinder mounted upon the
shaft and rotatable therewith within the
cylindrical casing, said abrading cylinder
being provided with open ends terminating
at a distance from the ends of the cylindrical
casing and with outwardly extending abrad-
ing members.

In testimony whereof we affix our signa-
tures in presence of two witnesses.

JAMES M. SMITH.
JOHN H. SMITH.
